UNITED STATES PATENT OFFICE.

FERNAND J. TILLMAN, OF ST. LOUIS, MISSOURI.

CARD FILE.

Application filed August 25, 1919. Serial No. 319,700.

To all whom it may concern:

Be it known that I, FERNAND J. TILLMAN, a citizen of the United States of America, and a resident of the city of St. Louis and State of Missouri, have invented a certain new and useful Improvement in a Card File, of which the following is a specification.

The primary object of this invention is to provide a simple means for preventing a card from being misfiled in any one of a number of card files.

Other and further objects will appear in this specification and be specifically pointed out in the appended claims, reference being had to the accompanying drawings exemplifying this invention and in which—

Fig. 1 is a reduced side elevation of a card file with the cards removed, and partly broken away to expose the partition walls that form compartments, each compartment adapted to contain 10 cards, and shows in each compartment two steps of different height, over which the cut-out portions of the cards of the respective compartments are adapted to fit.

Fig. 2 is a sectional view taken on line II—II of Fig. 1 enlarged and with the cards inserted, but with the cards and partition walls broken away to expose the steps of different height in the different compartments of the first half of the card file, over which the cut-out portions of the cards of the respective compartments are adapted to fit.

Fig. 3 is a diagrammatic view of three cards from the first three compartments of the first half of the card file with the center portions broken away and shows one wide cut-out portion in the left hand side and one narrow cut-out portion in the right hand side of each card which are adapted to fit respectively over the first three steps of the first half of the card file shown in Figure 2.

Fig. 4 is a sectional view taken on line IV—IV of Fig. 1 enlarged with the cards inserted and with the cards and the partition walls broken away to expose the steps

of different height in the different compartments of the second half of the card file over which the cut-out portions of the cards of the respective compartments are adapted to fit.

Fig. 5 is a diagrammatic view of three cards in the first three compartments of the second half of the card file with the center portions broken away and shows one narrow cut-out portion in the left-hand side and one wide cut-out portion in the right-hand side of each card which are adapted to fit respectively over the first three steps of the second half of the card file as shown in Figure 4.

Fig. 6 is a view of a card from a compartment of the first half of a card file partly torn away to expose a metal frame inserted in the card and shows the cut-out portions on each side of the card which are adapted to fit over the steps in its respective compartment in the card file and also shows cut-out portions in the lower edge of the card that are adapted to fit over correspondingly located bars in its respective card file.

Fig. 7 is a sectional view taken on line VII—VII of Fig. 1 and shows a card properly filed in its respective compartment in the first half of the card file.

Fig. 8 is a sectional view taken on line VIII—VIII of Fig. 1 and shows a card properly filed in its respective compartment in the second half of the card file and also shows a card from another card file prevented from being filed by means of bars located in the card file which shows that the card is not filed in its respective card file.

Fig. 9 is a repetition of the sectional view as shown in Fig. 8 and shows that a card from a compartment of the first half of the card file cannot be filed in a compartment of the second half of the card file.

Fig. 10 is a fragmentary view of the lower portion of a card file showing a card inserted in a reverse position.

Fig. 11 is a front view of a card file partly broken away to expose a card from one card file inserted into it and shows the

oblong cut-out portion of one card out of alignment with the oblong shaped bar in the card file indicating that the card belongs in a different card file, and also shows that the 5 cut-out portion in the sides of the card are of different height than the steps of the card file indicating that the card belongs in a different compartment.

Fig. 12 is a diagrammatic view of the 0 lower portion of a number of cards and shows in dotted lines the number of positions that the oblong shaped cut-out portions can take along the lower edge of a card and also shows in full lines in each 5 card different positions that the shouldered cut-out portion can take along the lower edge of the card.

Fig. 13 is a continuation of Fig. 12 showing 0 a number of positions that the oblong and shouldered shaped cut-out portions can 5 take along the lower edge of the card.

Fig. 14 is a continuation of Figs. 12 and 0 13 and shows a position that the oblong and shouldered-shaped cut-out portions can 5 take along the lower edge of the card.

Fig. 15 is a view of a number of different shaped sections of bars used in connection 0 with this invention.

Referring to the drawings 1 designates 5 one of a number of cards used in connection with this invention, each card being numbered in its upper right hand corner and inserted in each card is a metal frame 1^a, as shown in Fig. 6, containing an extension 2 which is adapted to be struck by a card selecting and raising device upon which a separate application for patent was filed on the same date Ser. No. 319,699 herewith. These extensions 2 are staggered in ten positions, 0 one extension 2 for each card representing the unit digit of the number on the card, and through these extensions 2 the cards 1 are adapted to be selected and raised by the card selecting and raising device. 3 is a 5 front wall, 4 is a back wall, 5 and 6 are side walls constituting a rectangular frame. Fastened to the side walls 5 and 6 and spaced between the front wall 3 and the back wall 4 are a number of partition walls (a) 0 which are for the purpose of forming compartments for separating each 10 cards, and a top portion (a¹) of the partition walls (a) is numbered to indicate each ten cards and a lower portion (a²) of the partition walls (a) 5 extends below the cards. The lower ends of side walls 5 and 6 are provided with angle portions 7 and 8 an upper part of which is adapted to serve as one of the resting portions for the cards 1 as shown in Figures 7, 8 and 11. This constitutes the card file and will hereafter be referred to as A.

As before stated the partition walls (a) 0 form compartments; each compartment is adapted to contain 10 cards and each parti-

tion wall (a) is numbered at (a¹) to indicate the cards filed in that compartment, that is, between the front wall 3 and the first partition wall (a) which is numbered 10 at (a¹) the cards numbered from 0 to 9 are adapted to be placed and between the first partition wall (a) which is numbered 10 at (a¹) and the second partition wall (a) which is numbered 20 at (a¹) the cards numbered from 10 to 19 are adapted to be placed, and between the second partition wall (a) which is numbered 20 at (a¹) and the third partition wall (a) which is numbered 30 at (a¹) the cards numbered from 20 to 29 are adapted to be placed, and so on throughout the length of the card file.

Upon side wall 5 as shown in Figs. 1 and 2 between the front wall 3 and the 50th partition wall (a) which is numbered 500 at (a¹) is a series of 50 wide steps or ledges 9, and it will be noted that the first step 9 starting from the front wall 3 is a low step and that each successive step throughout this half of the card file to the 50th partition wall (a) is one step higher. Upon the side wall 6 between the front wall 3 and the 50th partition wall (a) which is numbered 500 at (a¹) as shown in Figures 1 and 2 is a series of 50 narrow steps 10 and it will be noted that the first step 10 starting from the front wall 3 is a high step and that each successive step throughout this half of the card file to the 50th partition wall (a) is one step lower.

The cards numbered from 0 to 9 as shown in Fig. 3 are from the first compartment and are provided with a low wide cut-out portion 9^a on the left hand side and a high narrow cut out portion 10^a on the right hand side and it will be understood by comparing the cut-out portions 9^a and 10^a of the cards shown in Figure 3 and the first steps 9 and 10 of the card file shown in Fig. 2 that the cut-out portions 9^a and 10^a of the card numbered from 0 to 9 are adapted to fit over the first steps 9 and 10 of the card file A as shown in Fig. 2, and that the cut-out portions 9^a and 10^a of the cards which are numbered from 10 to 19 which are from the second compartment as shown in Fig. 3 are adapted to fit over the second step 9 and 10 of the card file A as shown in Fig. 2 and that the cut-out portions 9^a and 10^a of the cards numbered from 20 to 29 which are from the third compartment as shown in Fig. 3 are adapted to fit over the third steps 9 and 10 of the card file A as shown in Fig. 2 and it will be understood that the cut-out portions 9^a and 10^a of the cards will continue to match the different steps 9 and 10 of the different compartments throughout the first half of the card file, and it will also be understood that if a card from the first compartment containing cards numbered from 0 to 9 were placed in the third com-

partment adapted to contain cards numbered from 20 to 29 that the cut-out portion 9^a of the card would not fit over the step 9 of the card file because the cut-out portion 9^a of the card from the first compartment is not of the same height as the step 9 of the third compartment, and if a card from the third compartment containing cards numbered from 20 to 29 were placed in the first compartment adapted to contain cards numbered from 0 to 9, that the cut-out portion 10^a of the card would not fit over the step 10 of the first compartment of the card file, because the cut-out portion 10^a of the card from the third compartment is not of the same height as the step 10 of the first compartment of the card file A.

It will now be seen that a card from one compartment of the first half of the card file cannot be filed in any other compartment of the first half of the card file.

A method of preventing a card from being misfiled in the second half of the card file will now be described:

As before stated the partition walls (a) form compartments, each compartment adapted to contain ten cards, and each partition wall (a) is numbered at (a¹) to indicate the cards filed in that compartment, that is, between the fiftieth partition wall (a) which is numbered 500 at (a¹) and the fifty-first partition wall (a) which is numbered 510 at (a¹) the cards numbered from 500 to 509 are adapted to be placed, and between fifty-first partition wall (a) which is numbered 510 at (a¹) and the fifty-second partition wall (a) which is numbered 520 at (a¹), the cards numbered from 510 to 519 are adapted to be placed, and between the fifty-second partition wall (a) which is numbered 520 at (a¹) and the fifty-third partition wall (a) which is numbered 530 at (a¹) the cards numbered from 520 to 529 are adapted to be placed and so on throughout the second half of the card file A.

Upon the side wall 5 best shown in Figs. 1 and 4 between the fiftieth partition wall (a) which is numbered 500 at (a¹) and the back wall 4, is a series of 50 narrow steps 11 and it will be noted that the first step 11 starting from the fiftieth partition wall (a) is a low step and that each successive step to the back wall 4 is one step higher.

Upon the side wall 6 between the fiftieth partition wall (a) which is numbered 500 at (a¹) and the back wall 4 is a series of 50 wide steps 12 and it will be noted that the first step 12 starting from the fiftieth partition wall (a) is a high step and that each successive step throughout this half of the card file to the back wall 4 is one step lower. The cards numbered from 500 to 509 as shown in Fig. 5 are provided with a low

narrow cut-out portion 11^a on the left-hand side and a high wide cut-out portion 12^a on the right-hand side, and it can readily be understood by comparing the cut-out portions 11^a and 12^a of the cards shown in Fig. 5 and the steps 11 and 12 of the card file A as shown in Fig. 4 that the cut-out portions 11^a and 12^a of the cards numbered from 500 to 509 which are from the first compartment of the second half of the card file, are adapted to fit over the steps 11 and 12 of the first compartment of the second half of the card file as shown in Fig. 4 and the cut-out portions 11^a and 12^a of the cards numbered from 510 to 519 which are from the second compartment of the second half of the card file as shown in Fig. 5 are adapted to fit over the steps 11 and 12 of the second compartment of the second half of the card file as shown in Fig. 4 and that the cut-out portions 11^a and 12^a of the cards numbered from 520 to 529 which are from the third compartment of the second half of the card file as shown in Fig. 5 are adapted to fit over the steps 11 and 12 of the third compartment of the second half of the card file as shown in Fig. 4 and it will now be seen that the cut-out portions 11^a and 12^a of the cards will continue to match the steps 11 and 12 in different compartments throughout the second half of the card file A.

It will now be seen that if a card numbered from 500 to 509, which is from the first compartment of the second half of the card file, were placed into the third compartment of the second half of the card file, that the cut-out portion 11^a of the card would not fit over the step 11 of the card file A, because the cut-out portion 11^a of the card numbered from 500 to 509 which is from the first compartment of the second half of the card file, is not of the same height as the step 11 of the third compartment of the second half of the card file, and if a card numbered from 520 to 529 which is from the third compartment of the second half of the card file were placed in the first compartment of the second half of the card file, that the cut-out portion 12^a of the card would not fit over the step 12 of the first compartment of the second half of the card file A, because the cut-out portion 12^a of the card is not of the same height as the step 12 of the first compartment of the second half of the card file A.

It will now be seen that a card from one compartment from the second half of the card file cannot be filed in any other compartment in the second half of the card file.

Referring to Fig. 9 it will be noted that the card numbered 349 which belongs in the first half of the card file has been inserted in front of the partition wall (a) numbered 850 at (a¹) which is in the second half of

the card file and it will be seen that the narrow cut-out portion 10^a of the card does not fit over the wide step 12 of the card file A, therefore it can readily be seen that a 5 card from a compartment of the first half of the card file cannot be filed in a compartment of the second half of the card file, and that a card from the second half of the card file cannot be filed in a compartment of the 10 first half of the card file because the narrow cut-out portion 11^a of the card would not fit over the wide step 9 of the card file A, therefore it can readily be seen that a card from one compartment cannot be filed in any 15 other compartment throughout the length of the card file A.

20 *A method for preventing a card from being filed in a reverse position will now be described:*

Near the lower left hand side of the card file A, located between and fastened to the front wall 3 and the back wall 4 and passing under all the partition walls (a) is a triangular bar K, as shown in Figs. 2, 4, 7, 8, 9, 10 and 11. Near the lower left hand edge of each card is a triangular cut-out portion K' best shown in Fig. 6. This triangular cut-out portion K' is adapted to fit over the 25 triangular shaped bar K, and if a card were to be filed in a reverse position as shown in Fig. 10, that is, with the triangular cut-out portion K' on the right hand side of the card file in place of on the left hand side of the card file, the triangular bar K would prevent the card from being inserted, because the lower edge of the card would strike against the top of the triangular bar K.

20 *A method for preventing a card from being filed in a wrong card file will now be described:*

Cut in the lower edge of each card is an 5 oblong cut out portion E' and a shouldered cut-out portion F'. Between the front wall 3 and the back wall 4, and passing through all the partition walls (a) is an oblong bar E and a shoulder bar F and the oblong cut-out portion E' and the shouldered cut-out portion F' of the cards are adapted to fit over the oblong bar E and the shoulder bar F of the card file A, when the card is filed in its 10 respective card file. In the card file containing cards numbered from 0 to 999, the oblong bar E is placed near the left-hand side of the card file A as shown in Figs. 2, 4, 7, 8, and 9 and the cards which are numbered from 0 to 999 have the oblong cut-out portion E' cut to 15 fit over the oblong bar E in this position, and the shouldered cut-out portion F' is cut in the card to fit over the shoulder bar F in this file. In the card file containing cards numbered from 1000 to 1999, the oblong bar

E is moved over one position to the right 65 but the shoulder bar F is left in the same position near the center of the card file as shown in Fig. 11, and if a card from the card file adapted to contain cards numbered from 0 to 999 were placed in a card file 70 adapted to contain cards numbered 1000 to 1999, as shown in Fig. 11 the oblong cut-out portion E in the card would be out of alignment one position to the left of the bar E as shown in Fig. 11 and if a card from the card file adapted to contain cards numbered from 1000 to 1999 were to be placed 75 in the card file adapted to contain cards numbered from 0 to 999 as shown in Fig. 8 the oblong cut-out portion E' in the card would be out of alignment one position to the right with the oblong shaped bar E' of the card file A.

80 It has already been stated that each card file contains one thousand cards and that each card file contains two bars and in Figs. 12, 13 and 14 the lower portions of a number of cards show the number of different positions that the oblong cut-out portion E' and the shouldered cut-out portion F' can take along the lower edge of a card. The first card shown in Fig. 12 shows in full lines the oblong cut-out portion E' and the shouldered cut-out portions F' in the position that they take in the card file adapted 85 to contain cards numbered from 0 to 999 and the first card in Fig. 12 also shows in dotted lines twenty-four additional positions that the oblong cut-out portion E' can take along 90 the lower edge of the card without changing the position of the shouldered cut-out portion F'. 95

100 It will now be noted that the cut-out portion E' takes 25 positions in the first 25 card files and as each card file contains 1000 cards, it can readily be seen that 25000 cards are governed by the positions that the cut-out portion E' takes. It will be noted in the second card of Fig. 12 that the shouldered cut-out portion F' has been moved over one position to the left and that the oblong cut-out portion E' can take 25 positions along the lower edge of the card thereby governing 25 more card files or 110 25000 more cards making the total 50,000 cards, and every time the shouldered cut-out portion F' is moved one position to the left, it governs 25 additional card files or 25000 additional cards, and it can readily be seen 115 by referring to Fig. 14 that these two bars E and F govern 650 positions in 650 card files or 650,000 cards.

120 It will be noted in Fig. 15 that a number 125 of different shaped bars are shown, and as the use of bars E and F has just been explained, it can readily be seen that by using bar E in connection with bar G, that 650 more positions can be had by the combina-

tion of these two bars and therefore 650,000 additional cards are governed by these two bars and so on, as follows:

	E bar and F bar govern.....	650,000 cards	
	E bar and G bar govern.....	650,000 cards	
	E bar and H bar govern.....	650,000 cards	
	E bar and K bar govern.....	650,000 cards	
	E bar and L bar govern.....	650,000 cards	
	E bar and M bar govern.....	650,000 cards	
	E bar and N bar govern.....	650,000 cards	
	Total.....	4,550,000 cards	4,550,000 cards
10	F bar and G bar govern.....	650,000 cards	
	F bar and H bar govern.....	650,000 cards	
	F bar and K bar govern.....	650,000 cards	
	F bar and L bar govern.....	650,000 cards	
	F bar and M bar govern.....	650,000 cards	
	F bar and N bar govern.....	650,000 cards	
	Total.....	3,900,000 cards	3,000,000 cards
15	G bar and H bar govern.....	650,000 cards	
	G bar and K bar govern.....	650,000 cards	
	G bar and L bar govern.....	650,000 cards	
	G bar and M bar govern.....	650,000 cards	
	G bar and N bar govern.....	650,000 cards	
	Total.....	3,250,000 cards	3,250,000 cards
20	H bar and K bar govern.....	650,000 cards	
	H bar and L bar govern.....	650,000 cards	
	H bar and M bar govern.....	650,000 cards	
	H bar and N bar govern.....	650,000 cards	
	Total.....	2,600,000 cards	2,600,000 cards
	K bar and L bar govern.....	650,000 cards	
	K bar and M bar govern.....	650,000 cards	
	K bar and N bar govern.....	650,000 cards	
25	Total.....	1,950,000 cards	1,950,000 cards
	L bar and M bar govern.....	650,000 cards	
	L bar and N bar govern.....	650,000 cards	
	M bar and N bar govern.....	1,300,000 cards	1,300,000 cards
		650,000 cards	650,000 cards
	Grand total.....		18,200,000 cards

30 It will now be understood that if in place of the triangular bar K used to prevent a card from being filed in a reverse position a bar like bar E were used, 18,200 more combinations can be had, thereby governing 35 18,200,000 more cards as follows:

	Bar E in place of bar K governs.....	18,200,000 cards	
	Bar F in place of bar K governs.....	18,200,000 cards	
	Bar G in place of bar K governs.....	18,200,000 cards	
	Bar H in place of bar K governs.....	18,200,000 cards	
	Bar L in place of bar K governs.....	18,200,000 cards	
	Bar M in place of bar K governs.....	18,200,000 cards	
40	Bar N in place of bar K governs.....	18,200,000 cards	
	Total.....	145,600,000	

45 There are a number of other ways of increasing the number of combinations such as, offsetting the bars only half the width of the bars or of offsetting the bars only one-quarter the width of the bars, or by using different shaped bars, or by allowing more space along the lower edge of the cards so that more room can be made for 50 the bars.

What I claim is:

55 1. An index card having a cutaway portion formed on each end edge and extending a distance upwardly from the bottom thereof, one of the cutaway portions extending farther than the other.

60 2. An index card having a cutaway portion formed on each end edge and extending a distance upwardly from the bottom thereof, said cutaway portions providing upwardly arranged outwardly extending shouldered portions, one of said shouldered portions having a depth greater than the other shouldered portion.

65 3. A card file comprising side walls, card-

resting portions forming a part of the file, one of said side walls being provided with ledges arranged in step formation relative to one another, and a plurality of cards to be contained in the file adapted to engage 70 the card-resting portions, each having a co-operable portion formed thereon for a respective ledge of the file.

4. An index card adapted to be held on an edge in an approximate vertical position, 75 a receptacle for said card, and differently positioned identifying means provided on a pair of edges of the card cooperable with portions formed in said receptacle.

5. An index card adapted to be held on 80 an edge in an approximately vertical position, a receptacle for said card and differently positioned identifying means provided on opposing edges of said card cooperable with portions formed in said receptacle. 85

6. An index card having a cutaway portion formed on each end edge thereof, one of said cutaway portions extending a further distance upwardly than the other cutaway portion, thereby providing a pair of opposing shoulders which extend to the top edge of the card, one of said shoulders having a depth greater than the other shoulder. 90

7. A card file containing a plurality of 95 card-holding compartments, each compartment being provided with a pair of oppositely disposed card-fitting characteristics and adapted to contain a group of cards, each card of each card group having characteristics formed on opposing edges thereof for cooperation with the opposite characteristics of the compartment in which it is to be contained. 100

8. A card filing system, comprising a card-holding receptacle, said receptacle being divided into compartments, each compartment having a different card-fitting characteristic and adapted to contain a group of cards, each card of each card group having a characteristic conforming to the characteristic 110 of the compartment in which it is to be contained, all of the cards of the compartments bearing an alining notch and there being a portion extending longitudinally of the receptacle for engagement with the alining notches of said notched cards. 115

9. A card file containing compartments 120 each adapted to contain a number of cards, each compartment having a step portion formed on one of its side walls which is offset from those on the compartments next adjacent, each card having a cut-out portion formed on an edge for engagement with a respective step portion.

10. A card file containing compartments 125 each adapted to contain a number of cards, each compartment having a step portion formed on each of its side walls which are arranged on different horizontal planes, each card having a cut-out portion formed on 130

- opposing edges for cooperation with a respective step portion.
11. A card file containing compartments each adapted to contain a number of cards, 5 each compartment having a step portion formed on each of its side walls each card having a cut-out portion formed on opposing edges for engagement with said step portions, the step portions of each compartment being differently positioned relative to 10 one another.
12. A card file containing partitions forming compartments, each compartment being numbered for separating cards into groups, 15 each compartment having a step portion on each side thereof of different heights, and there being cut-out portions formed on each of the cards of each compartment cooperable with said step portions.
- 20 13. A card file having side walls in which are formed step portions of different heights, and there being cooperable portions formed on the cards contained in the card file, said cooperable portions of said cards providing 25 means for properly locating the cards in the file.
14. In a card filing system, a series of receptacles each containing a plurality of numbered compartments, a group of cards 30 located in each compartment, each card being numbered, each compartment having a differently located step portion, the cards of each card group each having a cut-out portion for the reception of the step portions of 35 their respective compartments.
15. In a card filing system, a series of receptacles, each containing a plurality of numbered compartments, each card being numbered, each compartment having a differently located step portion, the cards of each card group each having a cut-out portion for the reception of the step portion of 40 their respective compartments, all of the cards of each receptacle being provided with alining notches, the alining notches of the 45 cards of each receptacle being differently positioned and means extending the length of each receptacle for engagement with the alining notches of the cards of each respective receptacle.
- 50 16. A card filing system comprising a receptacle divided into a plurality of compartments each compartment being provided with a card resting portion and a card gaging ledge, the card gaging ledge of each compartment being on a plane higher than the card-gaging ledge of an adjacent compartment.
- 60 17. A card holding receptacle divided into a plurality of compartments for holding cards in approximately vertical positions each having a card gaging portion on one side, the card gaging portions of successive compartments being arranged in step formation to one another.
18. A card holding receptacle divided into a plurality of compartments for holding cards in approximately vertical positions, an end wall of each of said compartments having a ledge, said ledges being arranged in 70 step formation to one another from one end of the receptacle to a point intermediate of the ends of the receptacle, the compartments of the receptacle beyond the intermediate part thereof having other step formation 75 portions graduating oppositely to the step-formation portions which lead to the intermediate part of the receptacle.
19. A card file receptacle divided into a plurality of compartments, each compartment having a pair of opposing differently positioned ledges, the ledges of each compartment being on planes different than the ledges of an adjacent compartment. 80
20. A card file receptacle divided into a plurality of compartments, each compartment having a pair of opposing card engaging ledges, each ledge of each compartment being on a plane higher than each ledge of an adjacent compartment, each of said compartments being for the reception of a group of cards, each card of each group being provided with oppositely disposed shoulders which are adapted to cooperate with the 85 ledges of their respective compartments. 90
21. A card file containing a plurality of card-holding compartments, end walls for said compartments, one of the end walls of each compartment being provided with a card fitting characteristic differing from 95 those in the other compartments, each of said compartments adapted to contain a group of cards, each card of each group having a portion conforming to the characteristic of the compartment in which it is to be held. 100
22. A card file comprising side walls, each of said side walls being provided with card-cooperating means for permitting certain cards to be mounted in the file, said card-cooperating means of one of said walls being arranged in ascending step formation, the said card-cooperating means of said other side wall being oppositely disposed 105 from said first card-cooperating means and arranged in descending step formation. 110
23. A card file comprising side walls, each of said side walls being provided with card-cooperating means for permitting certain cards to be mounted in the file, said card-cooperating means of one of said walls being arranged in ascending step formation, the said card-cooperating means of said other side wall being oppositely disposed from 115 said first card-cooperating means and arranged in descending step formation, said file being divided into a plurality of transversely disposed card-holding compartments. 120
